(57) **CLAIM**

The ornamental design for a tray with compartments, as shown and described.

DESCRIPTION

FIG. 1 is a perspective view of my design;

FIG. 2 is a top view of my design;

FIG. 3 is a front view of my design, the opposite view being a mirror image thereof; and,

FIG. 4 is a side view of my design, the opposite side view being a mirror image thereof.

The graphics shown in broken lines in FIG. 2 are shown for illustrative purpose only and form no part of the claimed design.

1 Claim, 2 Drawing Sheets
